UNITED STATES PATENT OFFICE.

CLARENCE E. LOMAX, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed April 15, 1921, Serial No. 461,575. Renewed April 26, 1926.

The present invention relates in general to automatic telephone systems, but more especially to small systems such as are commonly known as private automatic exchanges; and the object of the invention is to provide an improved form of connector switch for use in a system of this kind. More specifically, a connector is provided which is of the monitor type, that is, it may 5 be used for supervising or monitoring busy lines and trunk lines, although it is used also by the official or other person to whom it is assigned for establishing all ordinary connections.

15 The invention may be better understood from a brief description of a private automatic exchange system in which it is adapted to be used. A system of this kind usually has a capacity of less than 100 lines and the 20 subscribers' lines are ordinarily provided with individual line switches which have access to a plurality of connector switches which are used for establishing local connections and also trunk connections to the 25 main exchange. When a calling subscriber removes his receiver his individual line switch is operated automatically and connects his line to an idle local connector switch, which responds to successive actuations of the calling device dial at the calling station to complete the connection to the desired local station, assuming that a local call 30 is being made. To handle trunk connections a group of trunk lines connecting with the 35 main exchange may be terminated in the local connectors, usually in the tenth level. In making a call to the main exchange, the calling subscriber will operate his calling device in accordance with the digit 0 and 40 when the local connector in use is raised to this level it operates automatically, somewhat in the manner of a selector switch, and establishes connection with the first idle trunk line encountered.

45 Now, in a private automatic exchange of the kind described established connections are entirely secret, because no operators are involved in the connections in any way, and this is a very desirable feature in that it 50 prevents operators, or other unauthorized persons, from listening to or otherwise interfering with established connections. A possible disadvantage, however, arises from

the fact that since the various employees 55 may establish connections themselves at any time, they may abuse the confidence reposed in them and may use the telephone system at unauthorized times, or talk about personal subjects entirely unconnected with the business. The present invention renders it 60 possible to detect such improper practice and at the same time it affords an official, or other person having supervisory authority, a convenient method of exercising general supervision over telephone traffic. 65

In its physical embodiment the invention comprises a special connector switch, which may be termed an "official connector", or a monitor switch. This connector is not intended for common use like the local connectors, but on the contrary is individual to the line of the official, or other person to whom it is assigned. It is used for establishing all ordinary local and trunk connections, and in addition has special circuit arrangements for performing the various monitoring or supervising functions which are necessary. These functions include the monitoring of busy local lines, and also the monitoring of busy trunk lines. The circuit arrangements are such that there is 70 no interference with automatic calling or with talking on lines which are being watched, and the parties using such lines 75 are not necessarily apprised of the fact that 80 their conversations are being listened to.

A further feature or modification may be used to advantage where an entire level is available as, for example, in a case where there are perhaps 80 or less local lines and 90 10 or less trunk lines to the main exchange, there being at least one level left which is not in use at the local connectors. This level may be used in the official connector and affords a very easy way of monitoring 95 calls where it is not necessary to know what particular lines are talking. The procedure is to multiple the trunk lines incoming to the local connectors in the particular level to be used for this purpose in the official 100 connector (usually the ninth level), and since there are only a relatively small number of connector switches, the person who is monitoring the calls can obtain access to all established connections very easily. 105

Referring now to the drawing in which

the invention is illustrated by means of the usual circuit diagrams, reference character A indicates a telephone substation of the usual automatic type which is assumed to be assigned to an official, or some other person who is authorized to supervise the telephone traffic. The line conductors 11 and 12 do not terminate in an individual line switch as is the usual practice, but extend directly to the special connector H, which is the official connector, or monitor switch previously referred to. This connector is a vertical and rotary switch of the usual Strowger type and is operated according to the well known two wire system of control. Of the ten levels of bank contact sets in the monitor switch only the first contact sets in the eighth, ninth and tenth levels are shown in the drawing. The first eight levels are assumed to be reserved for the local lines in the exchange and one of these lines, the line extending to the automatic substation A', is terminated in the first contact set in the eighth level shown in the drawing. The ninth level is utilized to give the monitor switch access to the local connectors for purposes previously explained, and contains a multiple of each of the trunk lines extending to such local connectors, one of these trunk lines, the one which terminates in the first contact set in the 9th level being shown in the drawing. The tenth level is used for trunk lines to the main exchange and one of these trunk lines is also shown, being terminated in the first contact set in the tenth level. It will be understood that all of the levels of the monitor switch, with the exception of the ninth level, are connected in multiple with the corresponding levels of the local connectors. The reference character C indicates a line switch which is individual to the line extending to the automatic substation A'. This line switch is of the well known rotary type in which the wipers have no normal position and move in a forward direction only.

The operation of the system will now be explained, it being assumed for this purpose that the official at the telephone substation A desires to establish connection with the subscriber at the local substation A'. When the receiver is removed a circuit is completed over the line conductors 11 and 12 for the double wound line relay 23 in the connector H. Upon energizing, relay 23 closes a circuit for the slow acting release relay 24. Upon energizing in turn, the latter relay prepares a circuit for the vertical magnet 30 at its armature 47 and at its armature 46 connects ground to the private normal conductor 14, the latter operation being effective to make the calling line busy to the local connector switches.

65 The calling device at substation A may

now be operated in accordance with the first digit in the desired number. As a result a series of interruptions is produced in the circuit of line relay 23 which is accordingly deenergized a plurality of times and at each 70 deenergization sends a current impulse to the vertical magnet 30 over the following path: From ground by way of armature 45 and its resting contact, armature 47 and its working contact, off normal springs 33 and 35, windings of the slow acting series relay 25, and the winding of the vertical magnet 30 to battery. By the operation of the vertical magnet, the shaft of the switch is raised step by step until the wipers 80, 81, and 82 80 are brought to rest opposite the desired horizontal level of bank contacts, which in this case is the eighth level. The slow acting relay 25 is energized in series with the vertical magnet 30 and by holding its armature 48 attracted throughout the vertical operation of the switch maintains the vertical magnet circuit intact after the off normal springs have been shifted, which occurs on the first vertical movement of the switch shaft. At the end of the vertical operation of the switch, relay 25 retracts its armature and transfers the operating circuit to the rotary magnet 31.

The calling device at substation A may now be operated in accordance with the second digit in the desired number, and as before a series of interruptions is produced in the circuit of the line relay 23. This time, upon deenergizing in response to the interruptions in its circuit, the line relay sends impulses to the rotary magnet 31 over the following circuit: From ground by way of armature 45 and its resting contact, armature 47 and its working contact, off normal springs 33 and 34, armature 48 and its resting contact, resting contact of armature 61 and the said armature, winding of the slow acting series relay 27 and the winding of rotary magnet 31 to battery. By the operation of the rotary magnet, the wipers 80, 81, and 82 are rotated step by step and are finally brought to rest in engagement with the particular set of bank contacts in which the desired called line is terminated. In the present case, since the called line is the line of substation A', which is terminated in the first set of bank contacts in the eighth level, the switch wipers will be rotated only one step and will be brought to rest in engagement with bank contacts 83, 84 and 85. The slow acting series relay 27 is energized in series with the rotary magnet 31 and remains in operated position throughout the rotary movement of the switch. At its armature 54, relay 27 connects the test wiper 81 to the winding of the test relay 28, while at armature 55 the connection between the two right hand windings of the repeating coil, which are nor-

mally bridged across the line wipers 80 and 82, is held open to prevent interference with busy lines during the rotation of the switch.

The operation now depends on whether the called line is busy or idle. If the line is busy there will be a ground potential upon the test contact 84 and the test relay 28 will be energized. When the slow acting series relay 27 falls back an instant after the rotary movement of the switch has been completed, a locking circuit is completed for relay 28 at armature 56, while at armature 57 the circuit of the upper winding of the switching relay 29 is opened to prevent this relay from pulling up. Relay 27 having de-energized, and the line wipers being in engagement with the bank contacts in which the called line is terminated, a talking or listening circuit is completed in an obvious manner, and the official at substation A will be able to listen to the conversation which is taking place between the party at substation A' and whoever it is that he is talking to. If the official desires to listen to the conversation for a few minutes to determine its character he may operate the transmitter cut-out button P at his telephone in order to render his own transmitter inactive. It will be observed that the connection as now established includes the windings of the repeating coil, and it will be observed further that the battery feed relay 22, which ordinarily supplies talking current to the called subscriber's line, has not been connected up because of the fact that the ring cut-off relay 26 has not been energized. With these circuit arrangements the official can listen in on the called line to good advantage, while at the same time he does not, in any way, interfere with the conversation that is going on and if the transmitter cut-out button is depressed, the establishment of the connection will ordinarily be effected without attracting the attention of the parties who are talking.

Two courses are now open to the calling party, assuming that he actually wishes to talk to the party at substation A'. He may hang up the receiver and call the number over again after a brief interval, or he may wait on the line until it becomes idle. Assuming that the latter course is followed, when the called line becomes idle the ground potential is removed from the test contact 84 and the test relay 28 will deenergize, thus closing a circuit for the switching relay 29 which extends from the grounded private normal conductor 14 by way of the resting contact of armature 57 and the said armature, the upper winding of switching relay 29, resting contact of armature 54 and the said armature, test wiper 81, test contact 84, private normal conductor 102, winding of the switching relay 104 of the line switch C and the winding of the stepping magnet 106

to battery. Upon the closure of the above circuit, relays 29 and 104 are energized in series, and the latter relay clears the line of substation A' of its normal battery and ground connections in the line switch C. It 70 may be explained that at the present time, due to an interlocking device controlled by the line relay 105, relay 104 is energized only about half way, and the wipers of the line switch are not connected up. 70

At the connector H, when the switching relay 29 is energized it establishes a locking circuit for itself at its armature 60, opens the rotary magnet circuit at armature 61, and at armatures 58 and 62 completes a signalling circuit for operating the ringer at substation A'. Ringing current from the generator GEN is now projected out over the called line in the usual manner to attract the attention of the subscriber at substation A'. The upper winding of the ring cut-off relay 26 is included in the circuit and when the called subscriber answers by removing his receiver from the hook relay 26 is energized, establishing a locking circuit 82 for itself at armature 51. In addition, relay 26 breaks the ringing circuit at armatures 49 and 53, closes a point in the talking circuit at the latter armature, and at armatures 50 and 52 connects up the battery feed 83 relay 22 for supplying talking current to the transmitter at the called station. The complete talking circuit has now been established and the two connected parties can converse as desired. 100

When the conversation is finished both the parties will hang up their receivers and the connector H is restored to normal by the replacement of the receiver at substation A. This operation opens the circuit of the line 105 relay 23 and relays 23 and 24 are accordingly deenergized, whereupon a circuit is completed for the release magnet 32. By the operation of the release magnet the connector switch is restored to normal position in 110 the usual and well known manner. Ground is also removed from the private normal conductor 14, which unlocks relays 26 and 29, and at the same time removes the busy condition from the line of substation A and renders it accessible to incoming calls. 115

It will be assumed now that the official at substation A desires to obtain a connection with someone in the main exchange. The operations which take place are substantially the same as those which have just been described, except that the calling device is operated in accordance with the number O¹ instead of the number 8¹, and the connector wipers, therefore, will be brought into engagement with the first contact set in the tenth level, the bank contacts comprising this contact set being indicated by the reference characters 89, 90, and 91. It should be stated further that when the switch shaft is 120 125 130 135 140 145 150 155 160 165 170 175 180 185 190 195 200

4

raised to the tenth level the cup spring casting at the top of the shaft engages with contact spring 37 and causes it to engage with contact spring 36, thus closing an energizing circuit for relay 21. Upon energizing, relay 21 disconnects the battery feed relay 22 and prepares a loop repeating circuit which will be described presently. Relay 21 also closes a circuit for the ring cut-off relay 26 which is energized and locked up for the purpose of opening the ringing circuit, as it is not necessary to ring out over the trunk line to the main exchange.

To continue with the operation of the connector H, and assuming that the wipers have been raised and rotated into engagement with the first set of contacts in the tenth level, if the first trunk line is busy the test relay 28 will be energized just as was described in the previous case and switching relay 29 will be prevented from operating. The same listening circuit is completed, however, when the slow acting relay 27 falls back at the end of the rotary movement of the switch and the party at substation A will be able to tell what is taking place on the trunk line. He may listen to the conversation that is going on if he considers it necessary, or if he desires to complete his own connection he will proceed to test the other trunk lines in order to obtain an idle one which may be used to set up the desired connection. This testing is accomplished by calling the digit 1 repeatedly until an idle trunk is located. When the digit 1 is called, the line relay 23 operates to transmit another impulse of current to the rotary magnet 31 and the switch wipers are advanced another step in order to connect with the second trunk line of the group. If this trunk line is busy also, the party at substation A will call the digit 1 again, and so on until a trunk line is found which is idle. When the wipers arrive at an idle trunk line, the test wiper 81 will find no ground potential on the bank contact which it engages and the test relay 28 will fall back and close the usual energizing circuit for the switching relay 29. For the purpose of describing the operations resulting from the energization of the latter relay it may be assumed that the first trunk line, or the line which terminates in bank contacts 89, 90 and 91, was found to be idle when connection was attempted therewith. Under these circumstances, switching relay 29 is energized at once as soon as the slow acting relay 27 falls back and performs its usual function, except that in this case no ringing circuit is completed due to the fact that the ring cut-off relay 26 has already been energized. In addition a bridge, referred to hereinbefore as a loop repeating circuit, is closed across the trunk conductors 92 and 94 as follows: from the conductor 92 by way of bank contact 89, wiper 80, upper right-

hand winding of the repeating coil, working contact of armature 50 and the said armature, armature 42 and its working contact, armature 59 and its working contact, armature 44 and its working contact, lower right-hand winding of the repeating coil, working contact of armature 53 and the said armature, working contact of armature 62 and the said armature, wiper 82, and bank contact 91 to the trunk line conductor 94. At the main exchange the trunk line conductors 92 and 94 may terminate in the line relay of an incoming selector switch, and by the closure of the bridge just described the line relay of this selector switch is operated. Upon energizing, the line relay closes a circuit for the associated slow acting release relay and the selector is prepared for operation in the usual manner.

The calling device dial at substation A may now be operated in accordance with the digits in the number of the party wanted at the main exchange, and as a result a plurality of series of interruptions is produced in the circuit of the line relay 23, which are repeated at armature 44 of the said line relay into the bridge across the trunk conductors 92 and 94, causing the incoming selector at the distant main exchange and a plurality of other switches to be operated to complete the desired connection to the called line. These operations are well understood and since the invention is not especially concerned with them it will be unnecessary to further amplify the explanation along this line. The connection is released the same as in the preceding case where a local connection was established.

Although in the foregoing it has been assumed that the official at substation A actually wished to establish certain connections, it will be understood clearly that substantially the same operations are gone through with in case it is desired merely to monitor or supervise certain local lines, or trunk lines. In the case of a trunk line to the main exchange, the party can listen in on all of the trunks within a short time by calling the number corresponding to the first trunk, which is the number 0¹, and then following up by calling the digit 1 at intervals until an idle trunk line is reached. If all of the trunk lines are busy it will be clear that they will all be connected with successively, thus permitting the official, or other person who is monitoring the calls, to find out what is going on on each trunk line. If an idle trunk line should be encountered before all of the trunk lines have been tested in this way the switching relay 29 will be energized and it will be necessary to hang up the receiver and release the connector switch, after which it is re-operated in accordance with the number of the next trunk line succeeding the line which was found to be idle.

The operation of monitoring calls by cutting in on the trunk lines leading to the local connectors will now be explained briefly. As pointed out before, these trunk lines are multiplied in the ninth level of the monitor switch, shown particularly in the case of the trunk line comprising conductors 110 to 112, inclusive, the line conductors of which are connected by means of conductors 108 and 109 with bank contacts 86 and 88, which bank contacts together with bank contact 87 comprise the first set of contacts in the ninth level. The operation of connecting with these trunk lines for monitoring purposes is precisely the same as was described in the case of monitoring the service on the outgoing trunk lines to the main exchange, with one exception however. Since all of the test contacts on the ninth level, such as the test contact 87, are left dead, the switching relay 29 cannot be energized, no matter whether the trunk line connected with is busy or idle; and it follows, therefore, that all of the local trunk lines may be tested or monitored by calling the number 9¹, which causes the monitor switch to connect with the first trunk line, and by following this up by calling the digit 1 at intervals in order to transfer the connection to all of the other trunk lines in succession. Since the switching relay 29 can never be energized during these operations, it follows that all of the local trunk lines and consequently all of the established connections in the private automatic exchange, whether local or trunk, can be listened in on within a very short space of time.

Before closing it may be pointed out briefly what takes place when the line of substation A is called. When one of the local connectors is operated by some other subscriber to connect with the line of substation A, the connection is established by way of the normal conductors 13, 14, and 15, and ground potential is placed on the private normal conductor 14 through the switching relay of the local connector which is in use. As a result, the cut-off relay 20 is energized to disconnect the line conductors 11 and 12 from the left-hand windings of the repeating coil, and to connect them instead with the normal conductors 13 and 15. There is nothing especially new in these operations, however, and it will be unnecessary to consider them further.

Having described my invention, what I consider to be new and desire to have protected by Letters Patent will be pointed out in the appended claims.

What I claim as my invention is:

1. In an automatic exchange, a monitor switch accessible to a telephone line, means whereby the subscriber on said line can operate said switch to establish connection with

another subscriber's line, means in said switch for automatically establishing a talking circuit between the two lines in case the second line is busy, means for ringing the called subscriber in case the second line is idle, means for establishing a talking circuit between said lines when the called subscriber answers, a battery feed coil, and means for connecting said coil to the talking circuit in the second case but not in the first.

2. In an automatic exchange, a monitor switch accessible to a telephone line, means whereby the subscriber on said line can operate said switch to establish connection with another subscriber's line, means for locking said switch on the called line in case the same is busy, means for establishing an inductive listening circuit to enable the calling party to hear the conversation on the called line, and means for automatically signalling the called subscriber when the called line becomes idle.

3. In an automatic exchange, a monitor switch accessible to a telephone line, means whereby the subscriber on said line can operate said switch to establish connection with another subscriber's line, means for locking said switch on the called line in case the same is busy, means for establishing an inductive listening circuit to enable the calling party to hear the conversation on the called line, means for automatically signalling the called subscriber when the called line becomes idle, inductive windings for feeding talking current to the called line, and means for altering the talking circuit connections to include said windings when the called subscriber answers.

4. In an automatic exchange, a monitor switch, telephone lines accessible to said switch, means for operating said switch from another telephone line to establish a circuit for listening on a busy called line, and means for further operating said switch without releasing the same to establish a circuit for listening on another busy called line.

5. In an automatic exchange, a monitor switch, telephone lines accessible to said switch, means for operating said switch from another telephone line to establish a circuit for listening on a busy called line, and means for causing successive further operations of said switch to successively establish other circuits for listening on a plurality of other busy called lines.

6. In an automatic exchange, a monitor switch, telephone lines accessible to said switch, means for operating said switch from another telephone line to establish a circuit for listening on a busy called line, means for causing successive further operations of said switch to successively establish other circuits for listening on a plurality of other busy called lines, and means for automatically preventing further operation.

of said switch in case an idle line is encountered.

7. In an automatic exchange, a monitor switch, a group of trunk lines accessible to said switch, means whereby the party to whom said switch is assigned can operate the same to connect with said trunk lines successively, it being unnecessary to release the said switch between successive connections, and means in said switch for establishing listening circuits to enable said party to listen on each connected trunk line as soon as it is connected with.

8. In an automatic exchange, subscribers' lines and individual line switches, trunk lines accessible to said line switches and leading to local connector switches having access to said subscribers' lines, a monitor switch having access to said subscribers' lines, and branches extending from said trunk lines to said monitor switch, whereby said monitor switch is given access to the said local connectors also.

9. In an automatic exchange, a plurality of subscribers' lines, a switch individual to each of said lines, trunk lines accessible to all of said switches in common and extending to local connector switches which have access to all of said subscribers' lines, and line terminals in one of said individual switches comprising a multiple of all the subscribers' line terminals in said local connectors.

10. In an automatic exchange, a monitor switch accessible to a telephone line, means whereby the subscriber on said line can operate said switch to establish connection with another subscriber's line, a relay in said switch energized while the switch is operating and deenergized when the called line is connected with, a talking circuit completed by said relay in case the called line is busy, another relay in said switch energized when the called line is connected with in case the same is idle, and contacts on said second relay for opening said talking circuit and for completing a signalling circuit.

11. In a telephone system, a calling line, a called line, a monitor switch individual to the calling line, means whereby the calling subscriber operates said switch in a vertical movement and then a rotary movement to connect with the called line, a relay in said switch energized during the rotary movement of said switch and deenergized shortly thereafter, line wipers and windings of a repeating coil in said switch, a series connection normally including the line wipers and two windings of the repeating coil in series, and contacts on said relay for opening said series connection at a point between the two windings of the repeating coil during the rotary movement of said switch, said contacts also reestablishing said series connection shortly after the rotary movement

is completed for establishing a listening circuit through the series connection for the calling line in case the called line is busy.

12. In a telephone system, a calling line, a called line, a switch accessible to the calling line, means whereby the calling subscriber operates said switch in a vertical movement and a rotary movement to connect with the called line, a relay in said switch energized during the rotary movement and deenergized shortly thereafter, contacts on said relay normally included in a talking circuit extending through said switch, said contacts opening the talking circuit during the rotary movement of said switch, and said contacts establishing a listening circuit for the calling line shortly after the rotary movement is completed in case the called line is busy.

13. In a telephone system, a calling line, a called line, a switch accessible to the calling line, means whereby the calling subscriber operates said switch in a vertical movement and a rotary movement to connect with the called line, a relay in said switch energized during the rotary movement and deenergizes shortly thereafter, contacts on said relay, line wipers and a repeating coil in said switch, and a talking circuit extending through said switch including said line wipers, said contacts, and the winding of said coil in series.

14. In a telephone exchange, a calling line, called subscribers' lines, a group of outgoing trunks extending to another exchange, a switch accessible to said calling line having access to said subscribers' lines and said group of outgoing trunks, means controlled by the calling subscriber for operating said switch to connect with either a called one of said lines or one of said outgoing trunks, means for signalling the called subscriber in case a subscriber has been called, a repeating coil in said switch, means responsive to the called subscriber answering for connecting talking battery over two windings of said repeating coil in series to the called line, and means operative responsive to the calling subscriber operating said switch to the group of outgoing trunks for preventing the operation of said signalling means and for preventing the connection of talking battery to any one of said outgoing trunks.

15. In a telephone exchange, a calling line, a switch accessible to said line, subscribers' lines and a group of outgoing trunks to another exchange terminating in the banks of said switch, means whereby the calling subscriber can operate said switch to connect with either a called one of said subscribers' lines or any one of said outgoing trunks, a repeating coil in said switch, means for feeding talking battery over two windings of said repeating coil in series to the subscribers' lines in case they are called, a relay

in said switch adapted to be operated only when the switch is operated to connect with one of said trunks, and means controlled by said relay for cutting out the battery feed 5 and for closing a bridge across the connected trunk including the windings of the repeating coil in series.

16. In a telephone exchange, a calling line, a switch accessible to said line, subscribers' lines and a group of outgoing trunks to another exchange terminating in the banks of said switch, means whereby the calling subscriber can operate said switch to connect with either said subscribers' lines or said outgoing trunks, means for feeding talking battery to the subscribers' lines in case they are called, line wipers, a condenser and windings of a repeating coil in said switch, a series circuit normally including the line wipers, 10 the condenser and two windings of the repeating coil in series, a relay in said switch adapted to be operated only when the switch is operated to connect with any one of said outgoing trunks, and means for operating 15 said relay in case the switch is operated to the group of outgoing trunks to cut off the battery feed and to short circuit said condenser thereby closing a bridge across any one of the outgoing trunks which may have 20 been called, said bridge including the line wipers, the short circuit around said condenser and the two windings of said repeating coil in series.

17. In a telephone system, a calling line, 25 a connector repeater switch accessible to the

calling line, subscribers' lines and outgoing trunks terminating in the banks of said switch, means whereby the calling subscriber can operate said switch to connect with either said subscribers' lines or said trunks, 30 line wipers, a condenser and windings of a repeating coil in said switch, a talking circuit including said line wipers, said condenser and two windings of said repeating coil in series established in case the switch has 35 been operated to a busy subscriber's line or a busy trunk, and means operated in case the switch is operated to an idle one of said trunks for short circuiting said condenser so as to enable the switch to repeat impulses 40 over said talking circuit to the idle trunk.

18. In a telephone system, an automatic switch, subscribers' lines and a group of outgoing trunks terminating in the banks of said switch, means whereby a calling subscriber can operate said switch to connect with either said subscribers' lines or said outgoing trunks, three different talking circuits in said switch, the first of said talking circuits established in case a busy subscriber's line has been called, means for establishing the second of said talking circuits in case an idle subscriber's line has been called, and means for establishing the third of said talking circuits in case an idle outgoing trunk 50 has been called and the connection completed 55 thereafter.

In witness whereof, I hereunto subscribe my name this 2nd day of April, A. D. 1921.
CLARENCE E. LOMAX.
